Specification for Design.

Patented May 18, 1920.

Application filed September 23, 1919. Serial No. 325,777. Term of patent 14 years.

To all whom it may concern:

Be it known that I, RUFUS J. HUTCHINS, a citizen of the United States, residing at Dayton, county of Montgomery, and State of Ohio, have invented a new, original, and ornamental Design for Casings for Water-Heaters, of which the following is a specification, reference being had to the accompanying drawing, forming a part thereof.

The design is illustrated in the accompanying drawing, to which reference is

made, and it comprises a casing for water heaters made in two parts hinged together, and of the contour shown in the drawing.

I claim:

The ornamental design for a casing for water heaters, as shown and described.
